DIRECTION SIGNAL

Harold N. Thomas, Topeka, Kans.

Application May 6, 1935, Serial No. 20,093

15 Claims. (Cl. 40—125)

This invention relates to a direction signal for use on highways as a warning and indication of directional changes and hazards in the highway ahead.

5 The object of the invention is to provide, in a manner as hereinafter set forth, a sectional arrow simulation structure having the sections thereof of such form and capable of being arranged relatively to each other as a single unit for indicating to the operator of a vehicle a hazard ahead, such as a right or left turn, a right or left curve or a combination of curves and turns which may occur on highways.

10 Further objects of the invention are to provide, in a manner as hereinafter set forth, a sectional direction signal which is simple in its construction, strong, durable, expeditiously assembled to designate the required signal, conveniently anchored in signaling position, thoroughly efficient 15 in its use and comparatively inexpensive to manufacture.

15 With the foregoing and other objects in view, the invention consists of such parts and such combination of parts, as are hereinafter more specifically described and illustrated in the accompanying drawing, wherein is shown several embodiments of the invention, but it is to be understood that changes, variations and modifications 20 may be resorted to which fall within the scope of the invention as claimed.

25 In the drawing:

Figure 1 is a front elevation of the signal for indicating a left turn,

Figure 2 is a front elevation of a modified form 30 of the signal for indicating a left curve,

Figure 3 is a front elevation of still another modified form of the signal for indicating an S-curve to the left,

Figure 4 is a perspective view looking towards 35 the inner side of the form of reversible head section employed in any one of the embodiments of the invention,

Figure 5 is a perspective view looking towards 40 the inner face of the form of reversible intermediate section employed as an element of the embodiment of the invention illustrated by Figure 1,

Figure 6 is a perspective view looking towards 45 the inner face of and showing the form of the reversible intermediate section employed as an element of the embodiments of the invention illustrated by Figures 2 and 3 and showing the form of the reversible foot section employed as an element of the embodiment of the invention illustrated by Figure 3, and

50 Figure 7 is a perspective view looking towards the inner face of and showing the form of the reversible intermediate section employed as an element of the embodiments of the invention illustrated by Figures 2 and 3 and showing the form of the reversible foot section employed as an element of the embodiment of the invention illustrated by Figure 3, and

55 the inner face of and showing the form of the foot section employed as an element of the embodiments of the invention illustrated by Figures 1 and 2.

With reference to Figures 1, 2 and 3, the signals are generally indicated at 5, 6 and 7 and each is of a form to simulate an arrow including a head formed of a single section and a stem consisting of an upper and a lower section. The upper section is termed an intermediate section 10 and the lower section a foot section. Each signal, as shown, consists of a head section, an intermediate section and a foot section. The head section is disposed at right angles to the other of said sections. In Figures 1, 2 and 3 the head 15 sections of the signals shown thereby are of like construction and are indicated generally at 8. In Figures 1 and 2, the foot sections of the signals 5 and 6 are of like construction and are generally indicated at 9. The intermediate section 20 of the signal 5 shown by Figure 1 is designated 10; that of the signal 6 shown by Figure 2 at 11; and that of the signal 7 shown by Figure 3 at 12. The foot section of the signal 7 shown by Figure 3 is indicated at 13 and is of the same form 25 as the section 12 of signal 7 but is oppositely disposed with respect thereto.

30 The head section 8 includes a flat substantially triangular shaped plate 14 having its base formed centrally thereof and projecting therefrom a flat neck 15. The base of plate 14, adjacent its point of emergence with the neck 15, is formed with a pair of oppositely extending rearwardly inclined edge portions 16, 17. Formed integral with the inner face of the plate and neck is an inwardly extending flange 18 coextensive and flush with and conforming in contour to the edges of the plate and side edges of the neck. Formed integral with the inner face and flush with the inner end of the neck 15 is a pair of spaced parallel apertured ears 19 disposed at right angles to said neck. The plate 14 is provided with a plurality of spaced openings 20 and tubular members 21 integral with its inner face and registering with openings 20. The plate 14 is also provided with a series of spaced openings 22 for the reception of reflex devices, not shown. The neck 15 has an opening 23 for the reception of a reflex device.

35 Each foot section 9 includes a flat rectangular plate 24 having formed integral with its inner face an inwardly extending flange 25 coextensive and flush with and conforming in contour to the lower end and side edges thereof. Formed integral with the inner face of, disposed at right 40

45

50

55

angles to and flush with the upper end edge of plate 24 is a pair of spaced apertured ears 26. The plate 24 is formed with an opening 27 and a tubular member 28 integral with its inner face and registering with opening 27. The member 28 is arranged in proximity to the lower end of the plate 24. The latter is also provided with a series of spaced openings 29 for the reception of reflex devices, not shown.

10 The intermediate section 10 of signal 5 comprises a flat angle-shaped plate 30 formed of a pair of legs 31, 32 disposed at right angles to each other. Formed integral with the inner face of plate 30 is a pair of spaced opposed parallel flanges 33, 33a. The flanges are coextensive and flush with and conform in contour to that of the side edges of plate 30. Formed integral with the inner face of plate 30 at each end thereof and disposed at right angles thereto is a pair of spaced parallel apertured ears. One pair is designated 34 and the other pair 35. At the point of mergence of the legs 31, 32 with each other, the plate 30 is formed with an opening 36. Integral with the inner face of plate 30 and registering with opening 36 is a tubular member 37. The plate 30 is provided with a series of spaced openings 38 for the reception of reflex devices, not shown.

15 The intermediate section 11 of signal 6 and the intermediate and foot sections 12, 13 respectively of signal 7 are of like form and each consists of a flat plate 39 of curved contour formed with a pair of spaced parallel inwardly extending flanges 40, 41 which are coextensive and flush with and conform in contour to that of the side edges of plate 39. Formed integral with the inner face of and extending at right angles to plate 39, at each end thereof, is a pair of spaced apertured ears. One pair is designated 42 and the other pair 43. The plate 39, at its transverse median, is provided with an opening 44 and has integral with its inner face a tubular member 45 which registers with opening 44. The plate 39 is formed with a series of spaced openings 46 for the reception of reflex devices, not shown.

20 The width of the sections 9, 10, 11, 12 and 13 are the same and correspond in width to that of extension 15.

25 The head section of each signal is reversible to extend in opposite directions; the intermediate section of each signal is reversible to extend in opposite directions and the foot section of signal 7 is reversible to extend in opposite directions. It will be assumed that the signal is to indicate a left turn, the head section would be as shown in Figure 1, the ears 35 of section 10 would be secured against the ears 19 of section 8 by the holdfast devices 47 and the ears 26 of section 9 would be secured to the ears 34 of section 10 by the holdfast devices 48. If the signal is to indicate a right turn, the section 8 is reversed from the position shown in Figure 1 to extend towards the right, section 10 is reversed from the position shown in Figure 1 to extend towards the right, ears 34 are coupled to ears 19 and ears 26 of section 9 are secured to ears 35. When the signal is to indicate a left curve the ears 42 of section 11 will be secured to ears 19 of section 8 by the holdfast devices 47 and ears 26 of section 9 will be secured to the ears 43 of section 11 by the holdfast devices 48. If the signal is to indicate a right curve the section 8 is reversed from the position shown in Figure 2 to extend towards the right, section 11 is reversed from the position shown in Figure 2 to extend towards the right, ears 43 of section 11 will be secured to ears 19 of sec-

tion 8 and ears 26 of section 9 will be secured to the ears 42 by the holdfast devices 48. When indicating an S curve from right to left, signal 8 will be as shown in Figure 3 with the ears 43 of section 12 secured to the ears 19 of section 8 and the ears 42 of section 13 will be secured to the ears 43 of section 12. If an S curve from left to right is to be indicated, sections 8, 12 and 13 will be reversed from the direction shown in Figure 3, ears 43 of section 12 will be secured to ears 19 of section 8 and ears 43 of section 13 will be secured to ears 42 of section 12.

20 The openings 22 and tubular members 21 of section 8, the opening 27 and tubular member 28 of a section 9, opening 44 and tubular member 45 of the sections 11, 12 and 13 are employed for the passage of holdfast means, not shown, for anchoring the signal in an upstanding position against a suitable support, not shown.

What I claim is:

1. In a combined direction and hazard indicating signal for highways, a sectional body including a head section, an intermediate section and a foot section, said intermediate section interposed between and having its ends abutting the inner ends of the said other sections, said intermediate section being reversible, means at the abutting ends of said sections for the passage of holdfast devices for detachably securing said sections in endwise abutting relation, and said sections provided with means for the passage of holdfast devices for anchoring said body in upstanding position against a support.

2. In a combined direction and hazard indicating signal for highways, a sectional body including a head section, an intermediate section and a foot section, said intermediate section interposed between and having its ends abutting the inner ends of the said other sections, said intermediate section being reversible, means at the abutting ends of said sections for the passage of holdfast devices for detachably securing said sections in endwise abutting relation, and said sections provided with means for the passage of holdfast devices for anchoring said body in upstanding position against a support, said intermediate section having that end secured to the head section disposed in non-aligning relation with respect to its other end to position the head section at right angles to the other of said sections.

3. In a combined direction and hazard indicating signal for highways, a sectional body including a head section, an intermediate section and a foot section, said intermediate section interposed between and having its ends abutting the inner ends of the said other sections, said intermediate section being reversible to selectively indicate the direction of travel to the right or left, means at the abutting ends of said sections for the passage of holdfast devices for detachably securing them in endwise abutting relation, and said sections provided with means for the passage of holdfast devices for anchoring said body in an upstanding position against a support.

4. In a combined direction and hazard indicating signal for highways, a sectional body including a head section, an intermediate section and a foot section, said intermediate section interposed between and having its ends abutting the inner ends of the said other sections, said intermediate section being reversible to selectively indicate the direction of travel to the right or left, means at the abutting ends of said sections for the passage of holdfast devices for detachably se-

- curing them in endwise abutting relation, and said sections provided with means for the passage of holdfast devices for anchoring said body in an upstanding position against a support, said 5 intermediate section having that end secured to the head section disposed in non-aligning relation with respect to its other end to position the head section at right angles to the other of said sections.
- 10 5. In a combined direction and hazard indicating signal for highways, a sectional body simulating the appearance of an arrow provided with an inwardly extending endless flange coextensive with the edges thereof, said body including a plurality of detachably connected abutting sections, and said body being formed with inwardly extending means for the passage of holdfast devices to anchor it upstanding to a suitable support.
6. In a combined direction and hazard indicating signal for highways, a sectional body formed 20 of a head section, and intermediate section and foot section, said intermediate section having its ends abutting the inner ends of the said other sections and being formed to dispose the head section at right angles to a portion thereof and to said foot section, said intermediate section being reversible endwise for selectively indicating different directions of travel, said sections being formed with inwardly extending flanges, the flanges of one section being arranged in endwise alignment with the flanges of an adjacent section, said sections being formed with means for the 30 passage of holdfast devices to detachably connect them together, and each of said sections having inwardly extending means for the passage of holdfast devices for the anchoring of said body in an upstanding position against a support when the sections are connected together.
7. In a combined direction and hazard indicating signal for highways, a substantially triangular shaped head section, an angle-shaped intermediate section having one end abutting one end of the head section, a foot section having one end abutting the other end of the intermediate section, the abutting ends of said sections being provided with means for the passage of holdfast devices for detachably connecting said sections together, the means at the said ends of said intermediate section providing for the reversing of the direction of the head section with respect to the intermediate section and the reversing of the direction of the intermediate section with respect to the foot section.
8. In a combined direction and hazard indicating signal for highways, a substantially triangular shaped head section, an intermediate section of curved contour having one end abutting one end of the head section, a foot section having one end abutting the other end of the intermediate section, the abutting ends of said sections being provided with means for the passage of holdfast devices for detachably connecting said sections together, the means at the said ends of said intermediate section providing for the reversing of the direction of the head section with respect to the intermediate section and the reversing of the direction of the intermediate section with respect to the foot section.
9. In a combined direction and hazard indicating signal for highways, a substantially triangular shaped head section, an intermediate section of curved contour having one end abutting one end of the head section, a foot section of segmental contour oppositely disposed with respect to and having one end abutting the other 70 end of said intermediate section, the abutting ends of said sections being provided with means for the passage of holdfast devices for detachably connecting said sections in endwise abutting relation, the said intermediate section being reversible relative to the head section to change the direction of the latter, the said intermediate section being reversible relative to the foot section to change the direction of the foot section relative to the intermediate section, the said foot section being reversible relative to the intermediate section to change the direction of the foot section relative to the intermediate section, the said sections being provided with inwardly extending means for the passage of holdfast devices for 75

anchoring them, when in abutting relation, to a support therefor, and each of said sections being formed with a plurality of openings for the reception of reflex devices therein.

- 5 13. In a combined direction and hazard indicating signal for highways, a head section formed of a horizontally disposed open rear substantially triangular shaped flanged body provided at its base with a flanged neck, an upstanding intermediate section formed of an open rear flanged body having its ends non-aligning and of a width corresponding to and having its upper end abutting said neck, an upstanding foot section formed of an open rear flanged body corresponding in 10 width to and having its upper end abutting the lower end of said intermediate section, and said neck, intermediate and foot sections having abutting means formed with openings for the passage of holdfast devices for detachably connecting said sections in endwise abutting relation.
- 15 14. In a combined direction and hazard indicating signal for highways, a head section formed of a horizontally disposed open rear substantially triangular shaped flange body provided at its base with a flanged neck, an upstanding intermediate section formed of an open rear flanged body having its ends non-aligning and of a width corresponding to and having its upper end abutting said neck, an upstanding foot section formed of an open rear flanged body corresponding in 20 width to and having its upper end abutting the lower end of said intermediate section, said neck, intermediate and foot sections having abutting means formed with openings for the passage of holdfast devices for detachably connecting said sections in endwise abutting relation, and said sections provided with inwardly extending means 25 for the passage of holdfast devices for anchoring said sections to a support therefor.
- 25 15. In a combined direction and hazard indicating signal for highways, a head section formed of a horizontally disposed open rear substantially triangular shaped flanged body provided at its base with a flanged neck, an upstanding intermediate section formed of an open rear flanged body having its ends non-aligning and of a width corresponding to and having its upper end abutting said neck, an upstanding foot section formed of an open rear flanged body corresponding in width to and having its upper end abutting the lower end of said intermediate section, said neck, 30 intermediate and foot sections having abutting means formed with openings for the passage of holdfast devices for detachably connecting said sections in endwise abutting relation, and said sections provided with inwardly extending means for the passage of holdfast devices for anchoring said sections to a support therefor, each of said sections being formed with a plurality of openings for the reception of reflex devices.

30
